A. L. LAMBERT

POST CONNECTION FOR VEHICLE BODIES

Filed April 27, 1925

Patented May 17, 1927.

1,629,278

UNITED STATES PATENT OFFICE.

ALBERT L. LAMBERT, OF PHILADELPHIA, PENNSYLVANIA, ASSIGNOR TO HEINTZ MANUFACTURING COMPANY, OF PHILADELPHIA, PENNSYLVANIA, A CORPORATION OF PENNSYLVANIA.

POST CONNECTION FOR VEHICLE BODIES.

Application filed April 27, 1925. Serial No. 25,968.

This invention relates to means for mounting a post on a vehicle body, especially on an automobile body, and the principal object of my invention is to provide simple and efficient means whereby a post may readily and easily be mounted, detachably, if desired, on a frame member of a vehicle body, and whereby the post is held in place with great sureness, firmness, and durability.

Other objects of my invention will be in part obvious and in part pointed out hereinafter.

In order that a clearer understanding of my invention may be had, attention is hereby directed to the accompanying drawings, forming a part of this application and illustrating certain possible embodiments of my invention. Referring to the drawings, Fig. 1 is a perspective view, showing a post attachment means secured to a vehicle body frame where a cross-piece meets a side sill, only fragments of the side sill and cross-piece being shown; Fig. 2 is a sectional view of the same, taken on the line 2-2 of Fig. 3, but includes an attached post; Fig. 3 is a horizontal sectional view of the same, taken on the line 3-3 of Fig. 2, showing a post in place; and Fig. 4 is similar to Fig. 2, but shows a modified construction which may be used when there is no cross-piece present, and also shows a modified manner of engaging the attachment bolts.

Similar reference characters refer to similar parts throughout the several views of the drawings.

Referring to the drawings, a vehicle frame member 1, which may be a side sill, is shown as being in the form of a box channel, having top wall 2, bottom wall 3, outer wall 4, and an inner wall formed of an upper wall portion 5, which meets a lower wall portion 6 along inwardly extending, abutting flanges 7. At the place where the post connection is to be made, the top wall 2, and the upper portion 5 of the inner wall of the frame member, are cut away, and here the post connecting member is permanently attached thereto. As shown, this member is constructed of two complementary sections, 8 and 9, each forming a vertical half of the connection. Referring to Fig. 1, section 8 has a vertical post engaging portion or wall 10, below which is a wing or web 11 extending to the left and arranged to come

against and to be welded or riveted to the inner face of outer wall 4 of the sill beneath its top wall 2. Along the right hand edge of wall 10 is an inwardly directed portion 12, from the upper part of which a flange 13 is broken off to the right, and from the lower part of which a wing 14 is broken off to the left so as to come against the inner face of sill wall portion 6 in position to be welded or riveted thereto. The complementary section 9 has a similar vertical post engaging portion or wall 15, below which is a similar wing or web 16 extending to the right and also arranged to come against and be welded or riveted to the inner face of outer wall 4 of the sill beneath its top wall 2. Along the left hand edge of wall 15 is an inwardly directed portion 17, from the upper part of which a flange 18 is broken off to the left, and from the lower part of which a wing 19 is broken off to the right so as to come against the inner face of sill wall portion 6 in position to be welded or riveted thereto. Preferably the portions 10 and 15 are in the same plane. The complementary flanges 13 and 18 are positioned to overlap each other, and to be secured together by welding or riveting. Thus the inwardly directed portions intermediate portions 10 and 15 form an exterior recess or channel. Bolt engaging means are disposed in this recess.

The post 20, to be connected, is channeled out to fit against the wall portions 10 and 15. A plate 21 is disposed against the opposite side of the post, and the securing of the post in place is effected by means of bolts 22, which extend through the plate 21, post 20, through perforations 23 formed therefor in the flanges 13 and 18 of the post connecting sections, and engage in threaded holes 24, which are formed in a metal block 25 disposed in the channel or recess of the connecting member, and which functions as a substitute for nuts for the bolts.

If a cross-piece 32 is present, where the post connection is to be made, for instance, a cross-piece of channel shape in cross-section, and open upwardly, the inwardly directed portions 12 and 17 of sections 8 and 9 may be formed to have inwardly extending arm portions, 27 and 28, between which is disposed and secured an inverted channel member 26, which has flanges 33 arranged

to rest on the bottom wall 34 of member 32 and to be welded or riveted thereto, thus securing a firm connection not only between the post and side sill, but also between the 5 post and cross-piece and between the sill and the cross-piece. As shown in Fig. 4, where there is no cross-piece, the arm portions 27 and 28 may be left off.

The upwardly extending portion of the 10 connecting member may or may not be flanged on the outside edges, as at 29, to overlap the side faces of the post 20, as desired.

Instead of providing the special nut member 25, nut pockets 30 may be formed out 15 of sheet metal to receive and hold ordinary nuts 31, and these pocket members with the nuts therein may be welded within the channel of the connecting member to hold the 20 nuts in position for engagement by bolts 22.

In the above manner an inexpensive post 25 connection is secured, and a connection which permits ready and easy attachment and detachment of a post, and which is adapted to hold a post rigidly and firmly against 30 loosening or displacement.

Preferably the sections 8 and 9 comprise 35 sheet metal stampings, but, if desired, they may be forgings or castings.

30 As many changes could be made in the above construction and as many apparently widely different embodiments of this invention could be made without departing from the scope thereof, it is intended that all matter contained in the above description or 35 shown in the accompanying drawings shall be interpreted as illustrative and not in a limiting sense.

What I claim is:—

40 1. A post connecting member of the character described, comprising two complementary sections, each having post engaging wall portions, and having adjacent inwardly directed portions forming an exterior recess between said wall portions, said sections having at said recess overlapping portions secured together.

45 2. A post connecting member of the character described, comprising two complementary sections, each having post engaging wall portions, and having adjacent inwardly di-

rected portions forming an exterior recess between said wall portions, said sections having at said recess overlapping portions secured together, and bolt engaging means in 55 said recess.

3. A post connecting member of the character described, comprising two complementary sections, each having post engaging wall portions, and having adjacent inwardly directed portions forming an exterior recess between said wall portions, said sections having at said recess overlapping portions secured together, bolt engaging means in 60 said recess, and a bolt penetrating said overlapping portions and engaging with said bolt 65 engaging means.

4. A post connecting member of the character described, comprising two complementary sections, each having post engaging wall 70 portions, and having adjacent inwardly directed portions forming an exterior recess between said wall portions, said sections having at said recess overlapping portions secured together, a post recessed to receive said 75 inwardly directed portion and fitting against the post engaging portion of the connecting member, and bolts extending through the post and engaging said means, for securing the post tightly to the post engaging portion 80 of the connecting member.

5. The combination with a hollow sheet metal sill having inner and outer wall portions, of a post connecting member comprising two complementary sections, each including wings abutting and secured to the interior surfaces of the inner and outer sill walls, and each including a post engaging wall portion extending above the outer sill 85 wall, said post engaging portions having adjacent inwardly depressed portions overlapping each other and forming an exterior recess between the wall portions, a post recessed to fit around said depressed portions and seating against the inside of said post 90 engaging wall portions, and bolts penetrating said post and overlapping portions and engaging a member seated in said recess.

This specification signed this 23rd day of April, 1925.

ALBERT L. LAMBERT.
